CHARLES M. BULLER, OF MILWAUKEE, WISCONSIN, ASSIGNOR TO L. J. MUELLER FURNACE COMPANY, OF MILWAUKEE, WISCONSIN, A CORPORATION OF WISCONSIN.

PIPE-SUPPORTING MEANS.

1,339,547.

Specification of Letters Patent.

Patented May 11, 1920.

Application filed April 6, 1917. Serial No. 160,176.

To all whom it may concern:

Be it known that I, CHARLES M. BULLER, a citizen of the United States, and resident of Milwaukee, in the county of Milwaukee, and State of Wisconsin, have invented new and useful Improvements in Pipe-Supporting Means, of which the following is a description, reference being had to the accompanying drawings, which are a part of this specification.

This invention relates to improvements in pipe supporting means more particularly adapted for hot air use.

Furnace pipes are usually formed of joints or sections telescoped together at their adjacent ends and are usually located in the spaces formed between the lath of the opposite walls and the studding therebetween during the construction of the walls. The pipes are of rectangular form in cross section and of a size to easily fit the wall spaces. It is very desirable to support these pipe joints or sections in order to relieve the joints of the strain of the weight and to maintain the pipes spaced from the studding. It has been the ordinary practice to solder projecting strips of metal to the pipes and then nail the free ends of the strips to the studding. This manner of attaching the pipes is objectionable as the solder does not always securely bind the strips to the pipe and in the event of separating the parts cannot be reattached due to the pipe being inclosed between the walls. Furthermore the projecting strips are very objectionable in shipping the pipes from the plant to the job and oftentimes break off.

It is one of the objects of the present invention to overcome the before mentioned objectionable features and provide a pipe supporting means which may be easily attached to the pipe without the use of solder and which may be moved to an inoperative position close to the pipe or easily connected to the pipe at the time of use.

A further object of the invention is to provide a pipe supporting means which in itself forms a means for attachment to the studding.

50 A further object of the invention is to provide a pipe supporting means which is of simple construction, is strong and durable and is well adapted for the purpose described.

55 With the above and other objects in view the invention consists of the improved pipe

supporting means and its parts and combinations as set forth in the claims and all equivalents thereof.

In the accompanying drawing in which 60 the same reference characters indicate the same parts in all of the views:

Figure 1 is a side view of a furnace hot air pipe shown positioned in a wall between the studding and secured thereto by the improved means;

Fig. 2 is a side view of a furnace hot air pipe provided with the improved supporting means; and

Fig. 3 is a transverse sectional view taken 70 on line 3—3 of Fig. 1.

Referring to the drawing the numeral 5 indicates a wall, 6 the studding thereof and 7 portions of furnace hot air pipe sections positioned between the studding. Furnace 75 pipes which extend vertically are usually of rectangular form in cross section and of a size to easily fit the spaces between the studding, and are also usually formed with an inner wall 8 and an outer wall 9 to form a 80 heat insulating space 10 therebetween. The pipe sections shown are joined together by a telescoping connection 11.

The improved supporting means comprises an elongated member formed of a 85 strip of metal 12 which is adapted to be inserted through an elongated slot 13 formed in the outer wall 9 of the furnace pipe 7. The slot 13 extends at an oblique angle with relation to the pipe so that when one end 90 portion of the member is inserted through the slot and into the insulating space of the pipe the outer portion of the member will extend upwardly and outwardly at an oblique angle of approximately forty-five 95 degrees. One of the outer corner end portions of the member is bent diagonally sharply at right angles to form an attaching tang 14 to be driven into the studding. 6. By bending the corner portion in the 100 manner described the width of the tang extends in the direction of the grain of the stud and may be easily driven therein. The member is also provided with an opening 15 to receive a nail 16 when it is desired to 105 more firmly attach the member to the stud.

The inner end of the supporting member 12 is bent at right angles and the bent end 17 is adapted to bear against the inner wall 8 of the pipe to hold the major portion of 110 the member in a position parallel to the outer wall 9 of the pipe. A tongue 18

formed medially of the length of the member is offset laterally inwardly from the plane of the major portion of the member and its free end extends in a direction toward the outer end of the member to lockingly hook under the edge portion of the outer wall 9 forming the elongated slot 13.

The tongue is cut and punched out from the metal of the member at a point distant 10 from the inner bent end 17 of the member greater than the distance the two walls of the pipe are spaced apart to prevent said supporting member from being turned at right angles to the wall through which it 15 extends and be removed.

In practice one of the supporting members is connected to the outer wall of the pipe adjacent opposite sides of the pipe to support the pipe firmly between two studs 20 as shown in Fig. 1.

In shipping the supporting members are pushed inwardly to a position in which the attaching tang will be close to one side of the pipe and only project the thickness of 25 the metal as shown in Fig. 2 and when desired they may be pulled out to attaching position.

From the foregoing description it will be seen that the pipe supporting means is of 30 simple construction and is well adapted for the purpose described.

What I claim as my invention is:

1. The combination with a vertically extending pipe provided with a side opening, 35 of a supporting means for said pipe consisting of an integral member slidably extending through the opening and lockingly engaging the pipe and having an outer end portion for attachment to a support.

2. The combination with a pipe provided 40 with a side opening, of a supporting means for said pipe consisting of an elongated strip of metal having a tongue formed medially of its length and an attaching means 45 formed on one end, said strip insertible through the side opening and the tongue lockingly engaging the edge portion of the wall surrounding the opening.

3. The combination with a pipe provided 50 with an elongated side opening, of a supporting means for said pipe consisting of an elongated strip of metal insertible through the elongated side opening and having a medial tongue which lockingly engages the edge 55 portion of the pipe surrounding the elongated opening, said elongated strip having its outer end portion bent to form an attaching tang.

4. The combination with a pipe provided 60 with an elongated side opening, of a supporting means for said pipe consisting of an elongated strip of metal insertible through the elongated side opening and having a medial tongue offset laterally from

the strip and which lockingly engages the 65 edge portion of the pipe surrounding the elongated opening, said elongated strip also having a locking tang formed on its outer end for engagement with a support.

5. The combination with a pipe having 70 an inner and an outer wall spaced from each other, the outer wall having an elongated opening extending therethrough, of a supporting means for said pipe consisting of an elongated strip of metal insertible through 75 the elongated opening of the outer wall and having an inner angular end portion which bears against the inner wall, said elongated strip also having an offset medial tongue which lockingly engages the edge portion 80 of the pipe surrounding the elongated opening, one of the outer end corner portions of the elongated member being bent at an angle to form a means for attachment to a support.

6. The combination with a pipe having 85 an inner and an outer wall spaced from each other, the outer wall having an elongated opening extending therethrough, of a supporting means for said pipe consisting of 90 an elongated strip of metal insertible through the elongated opening of the outer wall and having an inner angular end portion which bears against the inner wall, said elongated strip also having an offset medial 95 tongue which lockingly engages the edge portion of the pipe surrounding the elongated opening, the outer end portion of the elongated member provided with an opening and one of the outer end corner portions being bent at right angles to form a tang, said outer end opening and said tang forming a means for attachment to a support.

7. The combination with a pipe provided 100 with a side opening, of a supporting means 105 for said pipe consisting of an elongated strip of metal slidably connected to said pipe and movable from a position close to the walls of said pipe to a position in which its outer end projects at a distance from 110 said pipe and is provided with a tang for attachment to a support.

8. A supporting member for a pipe, consisting of an integral elongated straight strip of metal having bent opposite ends and 115 an offset medial tongue forming a locking means for engagement with a pipe having a side opening through which the strip of metal is adapted to slidably extend.

9. A supporting member for a pipe, consisting of an elongated strip of metal having a tongue cut from the strip medially of its length, one of the end portions of the strip bent at an angle to form an attaching tang and the other end of the strip being 125 bent at an angle to form a holding means.

In testimony whereof, I affix my signature.
CHARLES M. BULLER.
